CERTIFYING DEVICE FOR CASH REGISTERS

Biagio Beria, Turin, Italy

Application February 25, 1948, Serial No. 10,667
In Italy January 14, 1943Section 1, Public Law 690, August 8, 1946
Patent expires January 14, 1963

3 Claims. (Cl. 101—93)

1

This invention relates to cash registers, more particularly to apparatus for the double certification of bills, invoices and the like.

According to this invention the sheet feeding mechanism is arranged to vary the distance between the two impressions without replacing any part of the apparatus, merely by properly adjusting a movable part on a rotating cam.

The mechanism includes a slidable carriage to which the sheet is secured by means of a gripping member operated by a cam through a system of levers, after the sheet has been placed on the slidable carriage. During the movement of the carriage, the printing hammer is raised twice to print on the sheet the indications carried by the printing rollers.

The cam is of a profile composed of two diametrically opposed arcs of circles of different diameters, one end of the arc of smaller diameter merging into the corresponding end of the arc of greater diameter through a step and an arc of variable curvature, while the other end of the arc of smaller diameter merges into the corresponding end of the arc of greater diameter through an arc of variable curvature.

By the above-mentioned arrangement, when the invoice, bill or the like is slipped through a suitable aperture until it comes by its edge against the stop secured on the slidable carriage, and the machine is actuated at first the cam step comes into action and brings the gripping member into contact with the carriage in order to retain the sheet, next the printing hammer is operated to carry out on the bill or the like the desired registration, as the bill is held by the member retaining it to the carriage as mentioned above. On further rotation of the cam, the sheet is moved forward with the carriage toward the outside over the full period in which the operating lever runs from the profile of a smaller diameter to that of a greater diameter of the cam, whereupon the carriage stands still over the full time during which the lever is acted upon by the arc of a larger diameter. During this period the printing hammer comes into action for the second time and repeats the registration on another point on the bill or the like, the carriage is then returned by a spring to its initial position, while the sheet is momentarily retained by the printing hammer which remains a short time in its printing position.

The accompanying drawing shows by way of example a construction of the object of this invention.

Fig. 1 is a longitudinal sectional view of the

2

certifying device of the present invention on a plane parallel with the sliding direction of the carriage.

Fig. 2 is a plan view of the device, and
Fig. 3 is a detail elevational view of an actuating cam of the device.

Referring to the drawing, 1 denotes the table supporting the bill, invoice or the like, which is introduced into the machine through a suitable slit cut in the casing of the machine. A T-shaped carriage 2 is mounted over said plane in a suitable spaced relationship and is guided in its movement by lateral guides 3 secured by screws to the table 1.

15 A flange 4 is attached to the end of the carriage shank, and has anchored thereto the end of a spiral spring 5 which is wound about a roller 6 and is connected at its other end to a pivot 7 secured to the casing 8 of the conventional roller 20 mechanism feeding the ribbon by which the slips are issued by the usual manner by the cash register.

The flange 4 has fixedly connected thereto a tab 9 having pivoted thereto a rocking arm 10 carrying at its free end a gripping tongue 11 adapted to cooperate with the carriage head for gripping the sheet to be certified that has been introduced into the machine. In its inoperative position the tongue 11 is underneath the supporting table, in order to admit free introduction of the sheet.

The rocking arm 10 extending downwardly through slits cut in the carriage and in the supporting table, is provided with a tooth 12 coacting with a roller 12' fixed to the end of a lever 13 pivoted to a fixed pivot 50. The other end of the lever has fixed thereto a roller 13' which is acted upon by a cam 14 keyed on the driving shaft 15. The profile of said cam comprises an arc of a circle 16 having diametrically opposed thereto an arc of a circle 17 larger in diameter. One end of the arc 16 merges into the corresponding end of the arc 17 through a step 18 and an arc of varying curvature 18', while the other end 45 of the arc 16 merges into the corresponding end of the arc 17 through an arc 19 of varying curvature.

The casing 20 is arranged over the outer end 50 in the printing rollers 21 actuated in the usual manner by the mechanism of the cash register.

A wide slot 23 is cut in the supporting surface at the pad of the printing hammer which effects printing therethrough.

55 The printing hammer 33 is actuated in the fol-

lowing manner: the driving shaft 15 has secured thereto a second cam 30, which is provided with two teeth 31, 32. The printing hammer 33 is fixed to a lever 22 pivoted on a pivot 34 fixed to the frame of the apparatus. A second lever 35 is secured to the lever 22, said lever ending by a roller 36. The spring 37, having one end fixed to the lever 35 and its other end fixed to a point on the frame, constantly keeps the roller 36 in contact with the cam 30. One each turn of the driving shaft 15, the cam 30 raises twice the printing hammer 33, the teeth 31—32 being so arranged that the hammer is raised when the roller 13' contacts with cam 14 on the arc of a circle 16 or 17, respectively, that is, when the slideable carriage does not perform any relative movement with respect to the table 1.

In order to adjust the distance between the two certifications on the sheet, the cam 14 is comprised of two parts *a*, *b* connected together by means of slits 26 and clamping screws 27.

It will be obvious that by the above described arrangement, when the part *b* is moved outward as shown in Figure 3, the distance between both certifications is increased.

A stop 24 is provided on the carriage and projects downwardly into the clearance between the carriage and bearing table and serves for limiting the introduction of the sheet by the desired extent. The stop 24 is adjustably mounted by means of a pin-and-pivot fastening, in order to vary the position of both certifications simultaneously on the sheet.

The mechanism operates in the following manner.

The invoice, bill or the like is introduced into the machine, till its leading edge is brought against the stop 24 and the machine is set into action. On rotation of the cam 14 in the direction shown by the arrow, the roller 13' at the end of the lever 13 runs over the step 18 on the cam and the arm 10 is lifted to retain the sheet between the carriage 2 and gripping tongue 11.

The lever 22 is then actuated by the projection 32 on the cam 30 through the lever 35 and roller 36 and hammer 33 effects the first printing step. On further rotation of the driving shaft 15, the hammer 33 is lowered by spring 37 and the carriage is moved forward to expel the bill or the like over a certain distance, which is determined by the distance of the axis of the driving shaft 15 of the arcs of circles 16 and 17. As the arc 17 passes over the roller 13', the projection 31 on the cam 30 performs the second printing operation through the hammer 33 over levers 35 and 22 and roller 36.

The carriage 2 is in turn returned to its initial position by the spring 5.

Obviously, the form and constructional details may be varied in whatever manner to suit practical requirements without departing from the scope of this application.

What I claim is:

1. In an apparatus of the character described having a frame, a shaft, means for driving said shaft, a first and a second cam fixed on said shaft, a table fixed to the frame of the apparatus, a carriage slideable on said table, means secured to said table for guiding the slideable carriage in a rectilinear path, a stop fixed to said table for limiting the rearward movement of the slideable carriage, a spring having one end fixed to a projection on the slideable carriage and its other end secured to the frame so as to maintain the slideable carriage in its rearward

position, a stop secured to the slideable carriage, said second mentioned stop serving for limiting the introduction of a sheet to the desired extent, a lever pivoted to a pivot secured to the frame, 5 a roller mounted on each end of said lever, means for ensuring a constant contact between one of said rollers and the first cam secured to the driving shaft, a second lever pivoted to the slideable carriage, said second lever having a gripping tongue at one end and having a tooth contacting with said other roller mounted on the first mentioned lever, elastic means for ensuring a constant contact between said tooth and the roller contacting the same, the gripping tongue contacting in its raised position with one end of the slideable carriage, a printing hammer, a third lever pivoted to the frame and supporting at one end said printing hammer, a fourth lever secured at one end to said third lever and having fixed 10 to the other end a third roller, said third roller contacting with the second cam fixed to the driving shaft, elastic means for constantly holding said third roller in contact with said second cam, the second cam being shaped so as to raise 15 the printing hammer twice on each turn of the driving shaft, the first cam being shaped so as to displace the slideable carriage during one turn of the driving shaft so that said slideable carriage takes two positions of rest during one turn of 20 the driving shaft, said positions of rest corresponding to the raised position of the printing hammer.

2. In an apparatus of the character described having a frame, a shaft, means for driving said shaft, a first and a second cam fixed to said shaft, a table fixed to the frame of the apparatus, a carriage slideable on said table, means secured to said table for guiding the slideable carriage in a rectilinear path, a stop fixed to said table for limiting the rearward movement of the slideable carriage, a spring having one end fixed to a projection on the slideable carriage and its other end secured to the frame so as to maintain the slideable carriage in its rearward position, a stop secured to the slideable carriage, said second mentioned stop serving for limiting the introduction of a sheet to the desired extent, means for displaceably fixing said stop to the slideable carriage so as to vary the distance between the top of the sheet and the first certification, a lever pivoted to a pivot secured to the frame, a roller mounted on each end of said lever, means for ensuring a constant contact between one of said rollers and the first cam secured to the driving shaft, said cam having on its periphery two arcs of circles of different diameters, a second lever pivoted to the slideable carriage, said second lever having a gripping tongue at one end and having a tooth contacting with said other roller mounted on the first mentioned lever, elastic means for ensuring a constant contact between said tooth and said roller contacting the same, the gripping tongue contacting in its raised position with one end of the slideable carriage, a printing hammer, a third lever pivoted to the frame and supporting at one end said printing hammer, a fourth lever secured at one end to said third lever and having fixed to the other end a third roller, said third roller contacting with the second cam fixed to the driving shaft, elastic means for constantly holding said third roller in contact with said second cam, the second cam being shaped so as to raise the printing hammer twice on each turn of the driving shaft, the first cam being shaped so as to displace the slideable carriage during one turn of the driving shaft so that

said slidable carriage takes two positions of rest during one turn of the driving shaft, said positions of rest corresponding to the raised position of the printing hammer.

3. In an apparatus of the character described having a frame, a shaft, means for driving said shaft, a first and a second cam fixed to said shaft, a table fixed to the frame of the apparatus, a carriage slidable on said table, means secured to said table for guiding the slidable carriage in a rectilinear path, a stop fixed to said table for limiting the rearward movement of the slidable carriage, a spring having one end fixed to a projection on the slidable carriage and its other end secured to the frame so as to maintain the slid- 10 able carriage in its rearward position, a stop secured to the slidable carriage, said second mentioned stop serving for limiting the introduction of a sheet to the desired extent, means for displaceably fixing said stop to the slidable carriage so as to vary the distance between the top of the sheet and the first verification, a lever pivoted to a pivot secured to the frame, a roller mounted on each end of said lever, means for ensuring a constant contact between one of the said rollers and the first cam secured to the driving shaft, said first cam having a portion of its periphery defined by an arc of a circle of one diameter, a cam element adjustably mounted on said first cam for adjustment toward and away from the axis thereof and provided with a cam surface defined by an arc of a circle of a different diameter disposed opposite said peripheral portion so that said cam element may be brought toward or away from the axis of the driving shaft in order to in- 15 crease or reduce the spacing between the two cer- tifications on the sheet, a second lever pivoted to

the slidable carriage, said second lever having a gripping tongue at one end and having a tooth contacting with the other roller mounted on the first mentioned lever, elastic means for ensuring a constant contact between said tooth and the roller contacting the same, the gripping tongue contacting in its raised position with one end of the slidable carriage, a printing hammer, a third lever pivoted to the frame and supporting at one end said printing hammer, a fourth lever secured at one end to said third lever and having fixed to the other end a third roller, said third roller contacting with the second cam fixed to the driving shaft, elastic means for constantly holding said third roller in contact with said second cam, the second cam being shaped so as to raise the printing hammer twice on each turn of the driving shaft, the first cam being shaped so as to displace the slidable carriage during one turn of the driving shaft so that said slidable carriage takes two positions of rest during one turn of the driving shaft, said positions of rest corresponding to the raised position of the printing hammer.
